VANITY CASE

Jacques Kreisler, New Rochelle, N. Y., assignor
to Jacques Kreisler Manufacturing Corpora-
tion, New York, N. Y.

Application January 14, 1936, Serial No. 59,111

7 Claims. (Cl. 220—55)

The present invention relates to containers, and more particularly, to vanity cases and other containers designed for personal use.

One object of the invention is to provide a container having main and supplementary covers biased to open position by spring means and releasably held in closed position by fastening means which can be released by the actuation of a single push piece or other member operable externally of the container.

Another object of the invention is the provision of a vanity case or similar container having main and supplementary hinged covers biased to open position by spring means and releasably held in closed position by fastening means operable in succession to release the main cover first and subsequently to release the supplementary cover.

A yet further object of the invention is the provision of a vanity case or similar container having main and supplementary covers pivotally associated with the container on parallel axes and releasably held in closed position by catches which may be released by the actuation of a single push piece or other member operated externally of the container.

A yet further object of the invention is to provide a multi-cover container of the class described with improved fastening means for releasably holding the covers in closed position.

The above objects of the invention and other objects ancillary thereto will be best understood from the following description and the accompanying drawings:

In the drawings:

Fig. 1 is a perspective view of a vanity case constructed in accordance with the present invention, showing the main cover in open position, and the supplementary cover in closed position;

Fig. 2 is an enlarged transverse sectional view on the line 2—2 of Fig. 1, showing both covers in closed position;

Fig. 3 is a fragmentary horizontal sectional view on the line 3—3 of Fig. 2;

Fig. 4 is a detail sectional view on the line 4—4 of Fig. 3;

Fig. 5 is a fragmentary front view of the supplementary cover;

Fig. 6 is a detail sectional view on the line 6—6 of Fig. 2;

Fig. 7 is a view similar to Fig. 3, showing a modification;

Fig. 8 is a view similar to Fig. 3, showing another modification;

Fig. 9 is a detail sectional view on the line 9—9 of Fig. 8.

Referring to the drawings in detail, and first to Figs. 1 to 6, the container is illustrated as a vanity case 10 and comprises an outer receptacle having a bottom wall 12, side walls 14 and 16, and end walls 18. Said receptacle is provided with a main cover 20 which is hinged to the side wall 14 by a spring hinge 22, of any suitable construction, which tends to move said cover to open position. The cover 20 is provided with a rigid catch 24 by which the cover may be releasably held in closed position under the control of a movable latch 26, operated by a push piece 27 extending through the opening 29 in the side wall 16.

As here shown, the vanity case 10 may be provided with a powder compartment or tray 28 and a rouge or other cosmetic compartment or tray 30, formed in or carried by a frame 32 positioned within the vanity case. The powder compartment 28 is provided with a cover 34 pivotally associated with the case, on an axis parallel to the pivotal axis of the cover 20 by the spring hinge 36. Said hinge 36 may be of any suitable construction but as here shown it is constituted by the bent pin 38 extending through the eye 40 of the cover 34 and having its ends projected within bearing members 42 formed in said frame 32. The front edge of the cover has a depending flexible catch 44 provided with a projection 46 arranged to engage a part of the container, more specifically the frame 32, at the front edge 48 of an opening 50, for releasably holding said cover 34 in closed position.

As here shown, the cover is provided with a gasket 52 to seal the joint between the upper edge of the powder receptacle 28 and the cover. Also, as here shown, the cover 34 is formed with a depression 54 within which a powder puff (not shown) may be placed.

The latch 26 is constituted by the out-turned upper edge portion of a spring strip 31 positioned within the container, extending longitudinally of the side wall 16, and secured at one end to the frame 32 in any suitable manner, preferably by a rivet 33. The push piece is carried by the spring strip 31, being preferably soldered thereto, but said push piece may be separate from said spring strip in contacting relation therewith. Thus, by pressing on the push piece 27, the strip 31 is flexed away from the wall 16 and the latch 26 is released from engagement with the catch 24, thereby permitting the spring hinge 22 to move the main cover 20 to open position.

In accordance with the present invention, provision is made for moving the flexible catch 44

to cover releasing position by releasing said catch from engagement with the frame 32, preferably by the actuation of said push piece 27 in such manner that said supplementary cover 34 is released after the release of the main cover 20. This is accomplished by means including said strip 31, and a spring strip 56. Said spring strip 56 extends longitudinally of the side wall 16 and is secured at one end to the frame 32, in any suitable manner, preferably by a rivet 58 with its free end portion 57 overlapping the free end portion 35 of the spring strip 31 whereby said spring strip 56 may be moved toward the side wall 14 into engagement with the catch 44 to flex the latter out of engagement with the front edge 48 of the opening 50 in the frame 32, thereby to release the supplementary cover 34 to permit the spring hinge 36 to move said supplementary cover to open position. Thus, when both main and supplementary covers 20 and 34, respectively, are in closed position, it is possible to open only the main cover 20 or both said main and supplementary covers by the actuation of the push piece 27. If it is desired to open only the main cover 20, the push piece 27 is pressed inwardly a distance sufficient only to move the latch 26 out of engagement with the catch 24, and if it is desired also to open the supplementary cover 24, a further movement of the push piece 27 in the same direction is effective to bring the free end 35 of the spring member 56, thereby flexing the latter into engagement with the catch 44 to force the latter out of engagement with the frame 32 in the manner hereinbefore described.

In the modification shown in Fig. 7, the latch 26 for releasably engaging the catch 24 of the main cover 20 and the spring member for flexing the catch 44 to release the supplementary cover 34 are formed as integral portions of a single spring member 60. Said spring member 60 extends longitudinally of the side wall 16 of the container adjacent to said side wall, and has a reflexed portion 62 which is secured to the frame 32 in any suitable manner, as by rivets 64, whereby pressure on the push piece is effective to move the spring member 60 away from the side wall 16 thereby moving the latch 26 out of engagement with the catch 24 and subsequently, upon further movement of said push piece, to engage the flexible catch 44 to move the latter out of engagement with the frame 32, to permit only the cover 20 to move to open position, or to permit both covers 20 and 34 to move to open position in succession in the order mentioned.

In the modification illustrated in Figs. 8 and 9, the projection 47 on the rear side of the catch 44 engages the rear edge 49 of the opening 50 in the frame 32, and said catch 44 is released by flexing the same toward the side walls 16 instead of toward the opposite side wall 14, as in the previously described constructions. Also, in this modification, the means for releasing the catch 44 differs in construction from the catch releasing means of the other forms of the invention. As here shown, the catch releasing means comprises an L-shaped spring strip, having one branch 70 secured at one end to the frame 32 by a rivet 72, and a branch 74 extending longitudinally of the side wall 16 and carrying at its free end a cam block 76 provided with inclined surfaces 78 and 80, adapted to be engaged by the free end 35 of the spring member 31 and by the side edge 75 of the catch 44.

Thus, when the push piece 27 is pressed inwardly to release the catch 24, the spring member 31 is moved away from the side wall 16 of the vanity case, and upon further movement of said push piece, after the catch 24 is released, the free end 35 of the spring member 31 is brought into engagement with the inclined surface 78 of the cam block 76, thereby causing the branch 74 and the cam block 76 to move longitudinally of the side wall 16 or of the front wall 10 of the frame 32 whereby the inclined surface 80 of said cam block engages the adjacent side edge 75 of the catch 44 thereby causing said catch to move toward the side wall 16 whereby the projection 47 is forced out of engagement with the edge 49 of the frame opening 50 and the catch is released.

Thus, it is seen that each of the several embodiments illustrated herein is well adapted to accomplish the objects of the present invention. It will be understood, however, that the invention is capable of other specific embodiments and that in each of the constructions herein disclosed, certain changes may be made. Therefore, while the constructions here shown are suggested as preferred, I do not wish to be limited thereto except as may be required by the appended claims considered with reference to the prior art.

Having described my invention, what I claim and desire to secure by Letters Patent is:

1. In a case of the class described, comprising an outer receptacle having a main cover, an inner receptacle having a supplementary cover, a catch on each of said covers for holding the latter in closed position, a spring member having a latch adapted to engage the catch on said main cover for holding said main cover in closed position, a separate spring member adapted to be flexed into engagement with the catch on said supplementary cover to release the latter, said last mentioned catch releasing member being operated by said first mentioned catch releasing member, and a member operable externally of said case for actuating said first mentioned catch releasing member.

2. In a case of the class described, comprising an outer receptacle having a main cover, an inner receptacle having a supplementary cover, a catch on each of said covers for holding the latter in closed position, a spring member having a latch adapted to engage the catch on said main cover for holding said main cover in closed position, a separate spring member adapted to be flexed into engagement with the catch on said supplementary cover to release the latter, said last mentioned catch releasing member being operated by said first mentioned catch releasing member, and a push piece extending through an opening in a wall of said case for actuating said first mentioned catch releasing member.

3. In a case of the class described, comprising an outer receptacle having a main cover, an inner receptacle having a supplementary cover, a catch on each of said covers for holding the latter in closed position, a spring member having a latch adapted to engage the catch on said main cover for holding said main cover in closed position, a separate spring member adapted to be flexed into engagement with the catch on said supplementary cover to release the latter, said last mentioned catch releasing member being operated by said first mentioned catch releasing member, and a push piece carried by said first mentioned catch releasing member and extending

through an opening in a wall of said case for actuating said catch releasing members.

4. In a vanity case of the class described, comprising an outer receptacle having a main cover, an inner receptacle having a supplementary cover, a catch on each of said covers for holding the latter in closed position, the catch on said supplementary cover being flexible, a spring member having a part fixed to a part of said case adjacent one wall thereof and having a part adapted to be flexed away from said wall for releasing the catch on said main cover, and means operated by said spring member for flexing the catch on said supplementary cover to release the same.

5. In a vanity case of the class described, comprising an outer receptacle having a main cover, an inner receptacle having a supplementary cover, a catch on each of said covers for holding the latter in closed position, a spring fixed to a part of said case and adapted to be moved away from one wall thereof to release the catch of said main cover, and a spring member fixed to a part of said case and adapted to be flexed away from said wall to release the catch on said supplementary cover, said spring members having their free ends arranged in overlapping relation, whereby movement of said first mentioned spring member causes the movement of said second mentioned spring member, and means operable externally of the container for flexing said first mentioned spring member.

6. In a vanity case of the class described, comprising an outer receptacle having a main cover, an inner receptacle having a supplementary

cover, a catch on each of said covers for holding the latter in closed position, a member for releasing said catch of the main cover, and an L-shaped spring having one branch fixed to the container and its other branch provided with a cam block in engagement with a free edge of said first-mentioned catch releasing member and with the catch on said supplementary cover, whereby movement of said first-mentioned catch releasing member causes the free end of the latter to engage said cam block and forces the latter into engagement with the catch on said supplementary cover to force the latter into cover releasing position.

7. In a vanity case of the class described, comprising an outer receptacle having a main cover, an inner receptacle having a supplementary cover, a catch on each of said covers for holding the latter in closed position, a member for releasing said catch of the main cover, and an L-shaped spring having one branch fixed to the container and its other branch provided with a cam block in engagement with a free edge of said first-mentioned catch releasing member and with the catch on said supplementary cover, whereby movement of said first-mentioned catch releasing member causes the free end of the latter to engage said cam block and forces the latter into engagement with the catch on said supplementary cover to force the latter into cover releasing position, and means operable externally of said case for actuating said first catch releasing member.
